(57) **CLAIM**

The ornamental design for a support for a portable electronic device, as shown and described.

DESCRIPTION

FIG. 1 is a perspective view of a support for a portable electronic device showing our new design;

FIG. 2 is a second perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a perspective view of a second embodiment thereof;

FIG. 10 is a second perspective view of a second embodiment thereof;

FIG. 11 is a front elevational view of a second embodiment thereof;

FIG. 12 is a rear elevational view of a second embodiment thereof;

FIG. 13 is a right side elevational view of a second embodiment thereof;

FIG. 14 is a left side elevational view of a second embodiment thereof;

FIG. 15 is a top plan view of a second embodiment thereof; and,

FIG. 16 is a bottom plan view of a second embodiment thereof.
